UNITED STATES PATENT OFFICE.

ANNA OLSON, OF MANCHESTER, CONNECTICUT, ASSIGNOR TO THE CHENEY BROTHERS, OF SAME PLACE.

DESIGN FOR A HANDKERCHIEF.

SPECIFICATION forming part of Design No. 32,051, dated December 26, 1899.

Application filed November 29, 1899. Serial No. 738,732. Term of patent 3½ years.

To all whom it may concern:

Be it known that I, ANNA OLSON, a citizen of the United States, and a resident of South Manchester, in the county of Hartford and 5 State of Connecticut, have invented and produced a new and original Design for Handkerchiefs, of which the following is a specification, reference being had to the accompanying drawing, forming part thereof.

10 The figure is a plan view of a handkerchief, showing my new design.

As shown in the drawing, the leading or material feature of my design consists of the pictorial representation of a number of flags 15 shown in their appropriate colors and arranged about a central spot. Outside of the flags and around the edges of the figure a ribbon or border of irregular and wavy outline is displayed. The flags, as *a* and *b*, are disposed on opposite sides of the design and are 20 on staffs *c*, which cross each other and are united at the crossing-point by a ribbon-like border arranged in the form of a knot *d*.

A minor feature of the design consists of

the arrangement of four pairs of flags displayed on the crossed flagstaffs in diagonally opposite corners of the field, as at 1, 2, 3, and 4. Equidistant between the corners and on each side of the space the crossed flagstaffs *c* present a V-shaped opening, so that when 30 viewed as a whole the central field appears to be bordered by a serrated edge forming a star-like figure.

Another minor feature of the design consists of the shields 5, displayed at each corner 35 of the field and forming corner-pieces, and also at intervals between the pairs of flags on the crossed flagstaffs about the whole field.

What I claim as new, and desire to secure by Letters Patent, is—

40 The design for a handkerchief, as herein described and shown in the accompanying drawing.

ANNA OLSON.
